UNITED STATES PATENT OFFICE.

ROBERT J. STEWART, OF MOUNT CLEMENS, MICHIGAN.

SHIPPING-CASE.

1.110,157.

Specification of Letters Patent. Patented Sept. 8, 1914.

Application filed April 5, 1911. Serial No. 618,990.

To all whom it may concern:

Be it known that I, ROBERT J. STEWART, a citizen of the United States of America, residing at Mount Clemens, in the county of Macomb and State of Michigan, have invented certain new and useful Improvements in Shipping-Cases, of which the following is a specification, reference being had therein to the accompanying drawings.

10 This invention relates to packing or shipping cases, and it has for one of its objects the provision of an article of this character which may be built up from a single piece of sheet metal, and which possess great 15 rigidity.

The invention has furthermore for its object the improved construction of the blank from which the case is built, so that a large number of these blanks may be stacked together to form a comparatively small package.

20 Further objects of the invention will hereinafter appear and be particularly defined in the claims.

25 The invention has been clearly illustrated in the accompanying drawings in which similar characters denote similar parts, and in which—

Figure 1 is a perspective view of the blank 30 from which the case is to be built up, substantially in a series of successive steps which are shown in the next following figures, of which Fig. 2 illustrates the blank with its ends raised; Fig. 3 shows the front 35 in position; Fig. 4 illustrates the back and cover portions raised; Fig. 4^a shows a removable partition adapted for use in my improved case; Fig. 5 is the case complete and closed; Fig. 6 is an edge view of a portion of the blank, as *a* in Fig. 1, on an enlarged scale; Fig. 7 is a section on line 7—7 of Fig. 1; Fig. 8 is a top-view of corner *b* of Fig. 3; Fig. 9 is a horizontal section on line 9—9 of Fig. 3; Fig. 10 represents a fractional top view of the corner *c* of Fig. 5; Fig. 11 is a vertical section on line 11, 11 of Fig. 10; Fig. 12 is a vertical section on line 12, 12 of Fig. 5; Fig. 13 is a similar section on line 13, 13 of Fig. 5; and Fig. 14 45 illustrates a modification of the interlock between a pair of united case-sections.

The particular object of the present invention is: to provide a metallic shipping case or box of large size to replace the 50 wooden cases generally used for shipping dry goods, shoes, stationery, in fact any

bulky merchandise which is generally packed in strong cases. My improved case contains several advantageous features not found in the cases in ordinary use, as for instance it has greater strength in every way; it is lighter in weight, it is practically sealed against damage by rain, snow, or dirt; it can be sent to the shipper in flat condition; it takes less outside room or space for the same cubic contents; it will not burn; it permits goods to be packed so as to have an air-space all around them, without making any special provisions therefor; it is a one-piece device which does not require any screws, nails, clips or other extraneous fastening means; it can be built up into box-form in less time than it takes to assemble a wooden case; and it can be repeatedly used without requiring new parts. It is, of course, evident that the construction of the metallic case must be in accordance with its general dimensions and the purposes for which it is to be used, and I have illustrated in the accompanying drawings a three foot 70 shipping case for comparatively-heavy merchandise, the strengthening ribs being so disposed and interlocked that the case will sustain its handling during transit without danger of "opening" at its joints. 75

Referring first to Fig. 1, it will be noted that the blank consists of the several inclosing members in one single unitary structure, as for instance the bottom *B*, the front wall *F*, rear wall *R*, cover *C*, and end-walls *E*, *E'*. The blank has a series of ribs 80 formed by crimping the sheet-metal along those lines substantially in the manner shown in detail in Fig. 7, the crimps being closed tightly together to constitute practically a double-strength brace member or rib against strains which would tend to bend or buckle on lines parallel with the edge *a* (see Fig 1). Now, inasmuch as each of the ribs 20 is cut at each line 20' of the bend or junction between the adjacent sections *C*—*R*—*B*—*F*, it follows that these sections when bent into box-form as shown in Fig. 5, the corners thus formed will naturally resist crushing-strains at those lines. Furthermore it will be observed that the upper corners of each adjacent pair of ribs are slightly bent away from each other so that when the blank-sections are then bent at right angles, both rib-ends will become wedged and interlocked, and while there appears no means for preventing reopening or enlarging the 85 90 95 100 105 110

bend-angle of each individual pair of sections *per se*, yet these sections cannot be bent relatively to each other to form an acute angle between them, this circumstance being due 5 to the fact that the ends of the square-cut ribs will come to rest against the inner surfaces of said sections. It is therefore evident that the bends are strengthened against collapsing at several points along the bend-line, while the box-ends E', E'' will also 10 tend to maintain the case-corners in square condition.

The side margins of the sections C, R, and F, are crimped substantially as shown in detail at the left end of Fig. 7 in which the metal has a return-bend 21 which coacts with the rib 22 to form a channel 23. The channels pertaining to the side margins of the sections R and F are adapted to be placed 20 over the side-edges 24 (see Figs. 2 and 3) of the end-sections E', E'', when the latter are in their vertical positions, and these parts may be locked together by tabs 25 formed on the return-bends 21 of the sections R and 25 F and adapted to be passed through slots 26 in the end-sections E', E'', and bent over the inner faces thereof as shown at 25' in Fig. 9.

Attention is invited to the fact that in the present instance each end section (E', E'') 30 is provided with ribs 27, 28 formed in the same manner as above described, so that the end-sections will be efficiently braced.

Means are provided for holding the several rib-crimps in closed-together condition, 35 these means consisting preferably of portions of the ribs themselves as, for instance, is shown in Figs. 6 and 1, in which a portion of the extreme rib-end is cut to form a lip 30 which may be bent sidewise into flat contact with the body of the section, after which 40 the connection or joint is proof against being pulled apart by ordinary strains. The same construction applies to the extreme ends of all the ribs of the device.

The end-sections E', E'', are provided 45 with tabs 31 which, when the box is ready to be closed, will be in position to pass through slots or apertures 32 (see Fig. 4) provided therefor in the side edges of the 50 cover section C, whereupon they may be bent around the cover edge as shown at 31' in Figs. 5 and 12, thus holding the cover down at substantially central points of its side-edges. The front edge of the cover is provided 55 with slots 33 (see Figs. 4, 10 and 11) to receive the projecting ends 34 of the ribs of the front-wall section F, the organization being such that these ends are in close contact with the horizontal ribs of the cover, 60 so that, if now the outermost edge of these projections are bent over the cover to pass over the adjacent rib thereof, a very strong and close joint will be obtained along this front edge, and the parts will also be interlocked 65 against spreading of the ribs.

In order to protect the front edge of the cover from tearing out at the slots 33, I provide an overhanging ledge 35 which may be turned down when the cover had been closed.

In Fig. 14 I have illustrated a modification of the rib-construction which is here shown as a "double" rib instead of the single above described. This double rib constitutes a positive interlock in both directions when the adjacent box-section is bent into proper relation, and each rib interlock is depending upon itself for strength, in contradistinction to the simpler form previously described.

Inasmuch as it may be desirable to ship different kinds of goods in the same packing case, and that these different goods be kept separate from each other, I provide partitions 40 (see Fig. 4*) which may be readily placed into the case and held in position therein by channels or grooves as indicated at 41. Furthermore, by virtue of the fact that the ribs project inwardly from the inclosing walls, plates may be laid thereon to support goods in original cartons, etc., while an air space would be between these goods and box-sides, thus providing an additional element of safety for the goods.

The manner of building-up the box is 95 progressively shown in Figs. 1 to 5 inclusive of which Fig. 1 illustrates the blank substantially in its normal condition. In Fig. 2 the end-walls E', E'' have been bent upwardly. Fig. 3 shows the front wall 100 raised, Fig. 4 shows the double rear section (comprising the rear wall R and cover C) also raised, the cover C being still open and permitting access to the interior of the case to clinch the inner tab-ends of the front 105 and rear walls, and also to load the case and with merchandise, after which the cover may be bent down and locked by the tabs 34 and 31 which constitute the final closing 110 devices, and may be soldered if desired, thus rendering the case proof against thieves.

As will be seen, the ribs for the case are provided while the inclosing walls are in the blank form, thereby enabling the ribs of the strip which forms the front, bottom, rear 115 and cover walls to be made by crimping the entire strip and not the sections separately, the result being that the ribs are formed at a minimum expense, the blank simply being made of a sufficiently greater 120 width to provide the material for forming the ribs, and at the same time provide for a relative rib arrangement in which a series of ribs (those formed by the cutting of a single rib of the strip) will, when the blank 125 is folded, extend in approximate correspondence with a plane intersecting each of the wall sections which form the strip, the slight divergence of the adjacent ends of ribs to permit them to pass by during the folding 130

operation, not materially affecting the general continuity in length of the series of ribs, so that when the case is folded, there will practically be a rib continuous throughout the four walls, these ribs acting to brace the case against collapsing in one direction, the bends or folds acting in this respect in the opposite direction.

Many changes may be made in the general organization or union between the several members of my improved device without departing from the spirit of the invention, particularly in the rib-formation and the interlocking union between the adjacent members; and it is furthermore understood that rib-projections similar to those on the front wall F may be provided on all the ribs where a close and firm joint may be deemed expedient, especially in connection with the ribs 27 of the ends sections E' E'', which may have projections 27' adapted to pass through apertures as shown at r, in the adjacent sections R, F respectively.

I claim:

- 25 1. A packing case comprising a pair of foldable adjacent wall sections formed of a single piece of sheet metal, each of said sections being crimped to form closed-in ribs traversing both sections, said ribs being cut at the fold line, adjacent rib ends being moved out of longitudinal alinement to permit folding of the sections with the continuity of the rib line of the folded sections substantially maintained.
- 35 2. A packing case having one or more of its inclosing walls crimped to form inwardly-projecting ribs, means for holding said rib-crimps against opening, and a par-

tion plate having channeled side edges detachably engaging said ribs to form separate compartments in the case.

3. A packing case comprising alined adjacent wall-sections formed of a single piece of sheet metal, each of said sections being crimped to form inward ribs traversing all of said sections, said ribs being cut at the fold line, adjacent rib ends being moved out of longitudinal alinement to permit folding of the sections without materially affecting the continuity of the rib line of the folded sections, the edge of one end-section overlapping the margin of the opposite end-section, and means integral with the first named section for holding said sections in assembled position.

4. A packing case comprising alined adjacent wall and cover sections formed of a single piece of sheet-metal, each of said sections being crimped to form inward ribs traversing all of said sections, said ribs being cut at the fold line, adjacent rib ends being moved out of longitudinal alinement to permit folding of the sections without materially affecting the continuity of the rib line of the folded sections, the margin of the cover-section overlapping the edge of the opposite wall-section and having slots, and tabs on said wall section passing through said slots and bent over the cover section for holding both sections in locked position.

In testimony whereof I affix my signature in presence of two witnesses.

ROBERT J. STEWART.
